UNITED STATES PATENT OFFICE.

HALVER R. STRAIGHT, OF ADEL, IOWA.

TUNNEL KILN.

Application filed January 27, 1926. Serial No. 84,156.

This invention relates to a tunnel kiln for the burning of ceramic ware, and especially adapted for burning building materials and the like.

5 The object of my invention is to provide in a tunnel kiln in which the ware is moved continuously from the receiving end to the delivery end of the kiln improved means for introducing the combustible material there-

10 to.

A further object is to provide in a tunnel kiln improved means for imparting the proper circulation of air currents for the purpose of cooling the ware after it has 15 been burned, and also for the purpose of utilizing the heated currents of air for heating the ware before it reaches the maximum temperature zone.

A further object is to provide improved 20 means for stacking the ware on the kiln cars so that the cooling medium may be moved through the ware in a defined direction.

My invention consists in the construction, 25 arrangement and combination of the various parts of the device, whereby the objects contemplated are attained, as herein-after more fully set forth, pointed out in my claims and illustrated in the accompanying drawings, in which:

Figure 1 is a plan view of my improved kiln, a portion of the top of the burning zone being broken away.

Figure 2 is a side elevation of the same.

35 Figure 3 is a detail segmental sectional view taken on the line 3—3 of Figure 1.

Figure 4 is a detail segmental sectional view taken on the line 4—4 of Figure 1.

40 Figure 5 is an enlarged detail sectional view taken on the line 5—5 of Figure 1.

Figure 6 is a detail sectional view taken on the line 6—6 of Figure 5.

Figure 7 is a detail segmental sectional view taken on the line 7—7 of Figure 2.

45 Figure 8 is a detail segmental sectional view taken on the line 8—8 of Figure 2.

Figure 9 is a detail segmental sectional view taken on the line 9—9 of Figure 2.

50 Figure 10 is a perspective view of one of the fuel injecting devices.

Figure 11 is a perspective view of the deflecting and retarding members.

Figure 12 is a sectional view taken on the line 12—12 of Figure 2.

Figure 13 is a segmental sectional view 55 taken on the line 13—13 of Figure 2.

Figure 14 is a segmental sectional view taken on the line 14—14 of Figure 2.

Figure 15 is a segmental sectional view taken on the line 15—15 of Figure 2.

Figure 16 is a detail segmental sectional view taken on the line 16—16 of Figure 2.

Figure 17 is a segmental sectional view taken on the line 17—17 of Figure 2.

Figure 18 is a segmental sectional view 65 taken on the line 18—18 of Figure 2.

Figure 19 is a segmental sectional view taken on the line 19—19 of Figure 2.

My improved kiln is formed of a series of arched sections 10, 11, 12, 13, 14, 15 and 70 16 arranged end to end to form a continuous tunnel kiln. The sections 10, 11 and 12 form what I shall term the heating zone of the kiln, while section 13 forms the maximum temperature zone, and sections 14, 15 75 and 16 form the cooling zone. The sections are so arranged that a tunnel extends longitudinally through said kiln and is open at each end. The floor of the said tunnel is provided with track members 17 which are supported on suitable transversely arranged beams 18, which are preferably mounted in the floor of the kiln. The tracks 17 are designed to support and carry a series of tunnel cars 19, said cars being provided with supporting wheels 20. The top of each of the cars 19 is provided with a floor 21 formed preferably of a series of blocks 22 formed of fire clay. Said blocks 22 are arranged transversely on top of the 80 car and each of said blocks 22 is provided with a longitudinally extending opening or slot 23 which extends into the top of each of said blocks, so that a series of transversely and horizontally arranged passages 85 are provided in the floor member of the car. Said blocks 22 constitute what I shall term the floor.

The ware to be burned is stacked on the floor in the manner somewhat similar to that 100 shown in Figures 5 and 6, the ware being so stacked that a series of vertical passages 24 is provided the lower ends of which communicate with the passages 23. Each side edge of the stack of ware is formed with 105 a solid vertical wall 25 so that a definite up or down movement may be imparted to the cooling or heating medium as it passes

through the ware to be burned, as hereinafter made clear.

Extending longitudinally on the bottom of the kiln and at the outer sides of the tracks 17, I have provided an H-beam 26 secured to the members 18 by suitable brackets 27, said beams being placed in an inclined position, as clearly shown in Figure 5, so that a groove 28 will be formed in the top surface of each of said beams. These grooves 28 are filled with sand 29, or similar material, and serve to form means for providing a seal between the chamber below the cars and those on both sides of the cars. Each edge of each of the cars is provided with a downwardly extending plate 30, the lower edges of which extend into the sand 29. The cars 19 are run through the tunnel with their ends adjoining each other in such a manner that the ware stacked thereon will form a substantially continuous column of ware. Means not illustrated in the drawings is provided for imparting a substantially continuous and slow movement to said row of cars, said means forming no part of my present invention.

In order to provide a cheap, durable and economical construction for each of the kiln sections and at the same time provide the desired air circulation, hereinafter to be described, through the ware stacked on the kiln cars, I have formed the walls of each of said sections in the form of three arches, which I shall term the main arch 31, the by-pass arch 32 and the drop arch 33. The bases of the main arch are diverging, while the bases of the drop arch 33 simply terminate in the base of the by-pass arch. It will be seen in Figures 15, 16 and 19 that the drop arch 33 follows closely the contour of the upper surface of the stack of ware, said arch terminating in the by-pass arch at a point outside of and below the top edge of the said stack of ware. Figure 13 shows in cross section the shape of one end of the main arch, while Figure 14 shows in cross section the opposite end of said main arch. In Figure 13, it will be seen that the base portions of the forward end of the main arch 31 of section 16 are spread apart a considerable distance from the sides of the conveyor car, with the top portion of said arch following the contour of the top of the ware, so that comparatively large spaces 34 are provided at each side of the ware, while the space above the ware at this particular point is very much contracted. In Figure 14 the bases of the said arch are close to the sides of the kiln car, while the top of the arch extends considerably above the ware so a large space 35 is provided. Both ends of said arch are formed circular. The center of the arch section shown in Figure 13 is taken in a central vertical line at a point

considerably lower than the center of the arch section 14, in such a manner that in both sections of the arch the inner face of said arch is mounted close to the upper edge of the walls 25, so that three distinct longitudinal compartments are formed, one above the ware indicated by the numeral 35 and one at each side indicated by the numerals 34. The compartments 34 and 35 are brought into communication with each other through the vertical passages 23 and 24 in the stack of ware.

The outer end of the section 16 is provided with an end member 36 having air inlet openings 37, which are provided with supply pipes 38 connected to a suitable air circulating mechanism or fans 39, so arranged that the air will be delivered to the compartments 34 under pressure.

Adjacent to the inner end of the arch 31 of section 16 is the by-pass arch 32, shown in section in Figure 17. In this arch it will be seen that a considerable space is provided above the ware and at each side of the ware, and a passage 40 is provided adjacent to the upper ends of the walls 25, which causes the compartments above the ware and the compartments at the sides of the ware to be in communication. At the inner end of the by-pass arch 32 of section 16 is the drop arch 33 which is clearly shown in Figure 15. This provides a partition between the compartments 35 of section 16 and the compartments 35 of section 15.

Between the inner end of the arch 31 and the outer end of the arch 32 is a baffle wall 41, located adjacent to each side of the ware so that a division is provided between the compartments 34 of section 16 and the compartments 34 of section 15. It should be noted that the baffle walls 41 are at the outer end of the by-pass arch, while the drop arch 33 is at the opposite end of the by-pass arch so that a current of air moving longitudinally and inwardly through the passage 35 will be moved downwardly between the side walls of the by-pass arch and the walls 25 and into the passages 34 of section 15, in the manner hereinafter more fully set forth. Sections 14 and 15 are similar in all respects to section 16 and no further description of these sections is deemed necessary.

Sections 10, 11 and 12 are also similar to the construction of section 16 with the exception that they are arranged end to end and join onto section 13, forming the maximum temperature zone. This section 13 is also of arch construction and is illustrated in section in Figure 16. It will be seen that in said section considerable space is provided at each side as well as above the ware. The upper portion of said arch 13 is provided with a series of laterally and forwardly extending nozzles 42 arranged in two groups and extending inwardly and slightly down;

wardly. Each of the nozzles 42 is flattened at its inner end, as clearly illustrated in Figures 10 and 16. The nozzles of one group are in staggered relation with those of the other group as viewed from above. The nozzles of each of said groups are connected to suitable supply pipes 43, each of which is connected to a blower 44. Each of the supply pipes 43 is connected with a fuel supply pipe 45 designed to feed powdered or fluid fuel to the said pipes 43, so that as the blowers 44 are operated, a mixture of powdered or fluid fuel with the air will be fed into the kiln and ignited in the chamber above the ware. On account of the nozzles 42 extending inwardly and downwardly, it will be seen that the combustible fuel will be delivered downwardly through the ware and through the passages 24 and outwardly through the ends of the passages 23, causing recirculation in the manner shown by the arrows in Figure 16. On account of the nozzles being slightly pointed forwardly, the tendency to create a forward movement of the heated gases will also be maintained.

In the practical operation of my device the ware is stacked on the cars 19 in the manner clearly illustrated in Figures 5 and 6, with the upper portion of the stack of ware formed to substantially fit the under surface of the drop arches. The ware is fed into the left hand end of the kiln as illustrated in Figures 1, 2, 3 and 4, and moved continuously through the kiln at a slow speed, and the blowers 39 are operated as are also the blowers 44. Air is delivered to the passages 34 in section 16, which passes longitudinally of the ware and upwardly through the stack through the passages 23 and 24 into the compartment 35, where it is moved longitudinally and inwardly above the ware in section 16, until it reaches the drop arch 32. It is then moved downwardly between the walls of the by-pass arch 33 and the walls 25 of the stack of ware, and delivered into the compartment 34 of section 15, in which case it is again moved upwardly through the ware and again downwardly through the next by-pass section and again upwardly through the ware in section 14, and will be delivered directly into the compartment 13 above the ware, where the fuel is intermingled with the heated air from the cooling of the ware in sections 14, 15 and 16, at which time the heated gases will pass downwardly through the ware in the combustion zone and a certain amount of recirculation takes place, as previously described, so that the ware in this zone will become thoroughly heated. The gases then advance forwardly at a very slow speed and into engagement with the drop arch 33 of section 12, where they will be caused to pass under the ends of said drop arch into the by-pass arch 46. On account of the baffle walls 41 of sec-

tion 12, the gases will be moved upwardly through the compartment 35 above the ware, thence downwardly through the ware and into the compartments 34 of said section into the by-pass section 47 of section 11, and continuing in this manner until they reach the end of the kiln and pass outwardly through the stack 48 provided for that purpose.

In this connection it should be noted that it might sometimes be desirable to omit the drop arch 33 of section 12, permitting a portion of the gases from the upper compartment 13 to pass directly to the top of the compartment of section 12, thence downwardly through the ware, as before described.

By this arrangement it will be seen that as the ware is advanced from the combustion section 13, it will gradually become cooled as it is moved to the delivery end of said kiln. The air always moves upwardly through the ware, while passing through the cooling zone, thereby providing means whereby the circulation of the air will be easily established, due to its natural tendency to rise as it is being heated.

It will be seen, however, that as the air passes downwardly through the by-pass arches, it is working against its natural tendency to rise. To overcome this difficulty I have provided in each of the passages in the by-pass arch 32 of the cooling sections, a vertically arranged radiation plate 49, clearly shown in Figure 9, or what might be better termed a heat absorbing plate. The said plate is so arranged that a vertical passage 50 is provided, the upper end of which is connected to an air pipe 51 carried to the intake opening of one of the fans 44. The lower end of the passage 50 is provided with an opening 52 by means of which air will be caused to enter the passage 50. This air, being from the outside and cooler than the circulating air within the kiln, will cause the temperature of the cooling air, as it passes through the by-pass arch, to be reduced and the natural tendency for the current at that point to be downward. The plate 49 serves to heat the air which is used for combustion in the combustion chamber, thereby providing means for increasing the efficiency of the plant, as far as heating is concerned, as well as providing means whereby the natural circulation of the air through the kiln will be increased.

The gases passing through the by-pass arches of the heating zone, namely of sections 10, 11 and 12, will rise instead of fall, inasmuch as the gases are being cooled as they pass through this zone, and their natural tendency is to move downwardly as they pass through said by-pass arches. In order to overcome this difficulty, I have provided in the lower end of the by-pass passages of said by-pass arches burners 54,

which will cause the gases to be heated as they pass upwardly through said passages, thereby overcoming the natural tendency of the gases to move downwardly through said passages on account of cooling off. Any heat applied to the gases at this point serves to overcome the loss of heat, due to the cooling of the gases. The burners 54 are provided with suitable supply pipes 55.

10 I have found by actual practice that a considerable advantage is gained by heating the ware quite rapidly for a certain period of time, and then permitting the ware to rest or soak for a certain period of time, 15 then again rapidly increase the temperature and again permit the ware to pass through a soaking period.

I have also found advantage in cooling of the ware to provide certain soaking periods 20 in which an even temperature is maintained for a certain period of time. In order to accomplish these last results, I have utilized the by-pass arches of the sections of the kiln in the following manner:

25 In Figure 15, which is a section through one of these by-pass arches, I have illustrated at the lower end of the by-pass passages fillers 56, which are of such height that their upper surfaces are above the passages 30 23, thereby serving to act as a valve for closing said passages and to prevent any circulation through the ware as it passes through said by-pass arch, thereby permitting the ware to soak at whatever temperature it 35 happens to be while passing through the said arch. The soaking, however, may be carried on at any desired temperature by simply increasing or decreasing the length of the section or sections in front of the given by-pass 40 arch. That is, if the by-pass arch of section 15 is under consideration, then the temperature of the ware when passing through said arch may be determined by the temperature of the ware as it passes from the maximum 45 temperature zone, the length of the section 14 and the volume of cooling air passing through it. It will be seen that the temperature at this given section may be varied by either decreasing or increasing the volume 50 of air passing through the ware, or increasing or decreasing the length of section 14. After the proper length and volume have once been determined, the desired soaking 55 temperatures at these by-pass arches may be easily maintained. It will be seen that any one of these by-pass sections may be converted into a soaking zone by simply filling the lower end of the by-pass passages to close the end of the passages 23.

60 It will further be seen that by constructing the main arches of each section with their bases divergent, I have provided means whereby the sides of the passages 34 will be large at the intake end of said passages and contracted at the opposite end, so that the

gases will be forced quite uniformly horizontally through all of the passages 23 of the given section. By increasing the height of the arch at the delivery end of each section of the passages 35, I have also provided 70 means whereby this uniformity of the velocity of the gases through the passages 23 and 24 will be maintained, so that the heating or cooling of the ware may be rapidly accomplished, and at an increasing or decreasing 75 temperature from the burning zone to the discharge end of the kiln, or from the burning zone to the intake end of the kiln.

I have found, however, in practice that gases moving longitudinally through the 80 passages 34 establish a certain amount of momentum, which causes the pressure of said gases to be increased near the baffle walls 41, and the circulation through the passages 23 85 near these points to be increased. This difficulty I have overcome by providing in the vertical walls of the arch members 31 of sections 14, 15 and 16 a series of retarding blocks 57, a perspective view of which is shown in Figure 11. The blocks are so arranged that their inner ends project into the 90 passages 34 a certain distance. The front faces of the said blocks 57 are beveled so that the bases are deflected inwardly toward the ends of the passages 23. Said blocks 57 are 95 arranged in a staggered relation as shown in Figure 7, so that the longitudinal movement of the gases through the passages 34 is overcome to such an extent that the momentum of said gases will be brought to zero, thereby permitting a uniform velocity of the gases through the passages 23 and 24.

100 I have provided in the crown of the arches 31 of sections 10, 11 and 12, a similar arrangement of the blocks 57, said blocks being so arranged as to deflect the gases 105 downwardly into the upper ends of the passages 24, thereby preventing the increased pressure of said gases adjacent to the drop arches 31.

110 In the drawings I have shown the walls of the tunnel kiln as a series of arches of uniform thickness, which as a matter of fact are simply liners for the main wall construction, which is provided for the support of said arches. The exterior surfaces of these arches are provided with proper insulating materials, the construction of which is very common in kilns of this type. This construction forms no part of my present 115 invention, and for that reason it has not been illustrated in the drawings. It will readily be seen that further structure would be necessary in order to support arches of circular formation as illustrated herein.

120 It should be noted, however, that the arches 31 and 32 may be formed independently of each other, so that a contraction and expansion joint may be provided at the adjoining ends of said arches. The drop 125

arch 33 may be carried by either the by-pass arch 32 or by one end of the arch 31, preferably by the arch 32.

It will further be seen that by providing 5 the arch 31 of tapered formation, I have provided means whereby air passages of the desired shape may be easily and quickly constructed; and on account of being of an arch formation and properly supported by 10 a suitable wall construction which includes proper insulation, I have provided a wall construction which will withstand a large variation in temperature without buckling or deteriorating.

15 Thus it will be seen that I have provided a kiln of simple, durable and inexpensive construction, in which the temperature of the ware may be rapidly increased or decreased without cracking or warping the 20 ware, and in which any number of soaking zones may be established, and in which the circulation of the cooling or heating medium may be easily and uniformly maintained.

25 It will further be seen that I have provided improved means for supplying combustible materials to the combustion zone and in such a manner that the circulation of the combustible materials through said zone is very uniformly maintained, and in 30 which the temperature of said zone may be easily regulated.

It will further be seen that I have provided improved means whereby the momentum of the circulating gases may be overcome.

It will further be seen that I have provided improved method of stacking the ware on the cars, whereby the circulation through the ware may be moved in a defined direction without the use of an unnecessary amount of wall construction in the kiln.

I claim as my invention:

1. In a tunnel kiln for burning ceramic wares, means for supporting and moving 45 ware to be burned through said kiln comprising a heating zone, a maximum temperature zone and a cooling zone, means for delivering a cooling medium to the delivery end of said kiln, means for delivering 50 the cooling medium longitudinally along the sides of the ware as it passes through said kiln and through said cooling zone, and means for moving said cooling medium transversely beneath the stack of ware, thence upwardly through said ware, then 55 downwardly through the ware in said maximum temperature zone, and downwardly through the ware in the heating zone.
  2. In a tunnel kiln for burning ceramic 60 wares, means for supporting and moving ware to be burned through said kiln comprising a heating zone, a maximum temperature zone and a cooling zone, said heating zone and said cooling zone each being provided in a series of intermediate sections,
- means for introducing a cooling medium along the sides of the ware in one of said cooling sections, then horizontally beneath the bottom of the ware and upwardly through it, thence downwardly past the sides 70 of the ware in the second section of said cooling zone, thence upwardly and again through the ware, thence downwardly through the ware in said maximum temperature zone, thence upwardly past the side 75 to the top in one of the sections of said heating zone, thence downwardly through the ware in said section, thence horizontally and outwardly and longitudinally and upwardly along the side of said ware to the 80 top of the ware in the second section of said heating zone and downwardly and outwardly as described.
3. In a tunnel kiln for burning ceramic 85 wares, means for supporting and moving ware to be burned through said kiln comprising a heating zone, a maximum temperature zone and a cooling zone, said heating zone and said cooling zone each being 90 provided in a series of intermediate sections, means for introducing a cooling medium along the sides of the ware in one of said cooling sections, then horizontally beneath the bottom of the ware and upwardly through it, thence downwardly past the sides 95 of the ware in the second section of said cooling zone, thence upwardly and through the ware of said second section, thence downwardly through the ware in said maximum temperature zone, thence upwardly 100 to the top of the ware in one of the sections of said heating zone, thence downwardly through the ware in said section, thence horizontally and outwardly and longitudinally along the sides of said ware, thence upwardly along the sides of the ware to the top of the ware in the second section of said heating zone and downwardly 105 and outwardly as before described, and means for preventing the direct flow of the cooling or heating medium through the ware as it passes from one section to another section.
4. In a tunnel kiln for burning ceramic 110 wares, means for supporting and moving ware to be burned through said kiln comprising a heating zone, a maximum temperature zone and a cooling zone, said heating zone and said cooling zone each being 115 provided in a series of intermediate sections, means for introducing a cooling medium along the sides of the ware in one of said cooling sections, then horizontally beneath the bottom of the ware and upwardly through it, thence downwardly to the sides of the ware in the second section of said cooling zone, thence upwardly and again through the ware, thence downwardly 120 through the ware in said maximum temperature zone, thence upwardly to the top of the 125

ware in one of the sections of said heating zone, thence downwardly through the ware in said heating section, thence horizontally and outwardly and longitudinally along the 5 sides of said ware, thence upwardly along the sides of the ware to the top of the ware in the second section of said heating zone and downwardly and outwardly as before described, and means for introducing a combustible material and air into the upper portion of said maximum temperature zone.

5. In a tunnel kiln for burning ceramic wares, means for supporting and moving ware to be burned through said kiln comprising a heating zone, a maximum temperature zone and a cooling zone, said heating zone and said cooling zone each being provided in a series of intermediate sections, 10 means for introducing a cooling medium along the sides of the ware in one of said cooling sections, then horizontally beneath the bottom of the ware and upwardly through it, thence downwardly to the sides of the ware in the second section of said cooling zone, thence upwardly and again through the ware, thence downwardly through the ware in said maximum temperature zone, thence upwardly to the top 15 of the ware in one of the sections of said heating zone, thence downwardly through the ware in said section, thence horizontally and outwardly and longitudinally along the sides of said ware, thence upwardly along the sides of the ware to the top of the ware in the second section of said preheating zone and downwardly and outwardly as before described, and means for introducing a combustible material and air into the upper portion of said heating zone, the last 20 40 said means being arranged in two groups, each of said groups comprising a series of fuel introducing nozzles, the nozzles of one group being in staggered relation with those of the other group, said nozzles being inclined inwardly and downwardly.

6. In a tunnel kiln for burning ceramic wares, means for supporting and moving ware to be burned through said kiln comprising a heating zone, a maximum temperature zone and a cooling zone, each of 45 said heating and cooling zones being divided into a series of intermediate zones, the spaces between the adjoining ends of the intermediate sections of said heating and cooling zones being provided with a by-pass section, each of the by-pass sections of said cooling zone being provided with cooling means, each of the by-pass sections of said heating zone being provided with heating means, the sections of said cooling zone being so arranged that the cooling medium will pass upwardly through the ware as it 50 passes through said zone and downwardly through said by-pass sections, the sections 55 of said heating zone being arranged in such

a manner that the heating medium will pass downwardly through the ware and upwardly through said by-pass sections, and means for introducing fuel to said maximum temperature section.

7. In a tunnel kiln for burning ceramic wares, means for supporting and moving ware to be burned through said kiln comprising a heating zone, a maximum temperature zone and a cooling zone, each of said zones being divided into a series of intermediate zones or sections, means for reducing the temperature of the ware as it passes from the receiving end of said cooling zone to the delivery end of said zone, means for providing soaking zones between the receiving end and delivery end of said cooling zone, means for increasing the temperature of the ware as it is moved from the receiving end to the delivery end of said heating zone, and means for providing soaking zones between the receiving end and delivery end of said heating zones.

8. In a device of the class described, a tunnel of circular formation in cross section, a tunnel car designed to be moved longitudinally through said tunnel, the top of said car being provided with a floor having transversely arranged grooves in its top surface, said grooves being opened at their ends, ware to be burned being stacked on said floor in such a manner that vertical passages will be formed, the sides of said stack of ware being piled so as to provide a solid vertical wall, the upper edges of said walls being designed to move in close proximity to the inner surface of said arch so that a longitudinal passage will be provided above the ware and one at each side of said ware, the passage above 105 said ware being in communication with the passages at the sides of said ware through the horizontal passages of said floor and the vertical passages of said ware.

9. In a tunnel kiln for burning ceramic wares, means for supporting and moving ware to be burned through said kiln comprising a heating zone, a maximum temperature zone and a cooling zone, each of said cooling and heating zones being divided into 110 a series of intermediate zones, the wall construction of each intermediate zone comprising a main arch, a by-pass arch and a drop arch, the bases of said main arch being arranged in a diverging manner relative to each other, the bases of said by-pass arch being substantially parallel, the contracted ends of the base members of said main arch supporting an arch higher than the arch portion of the diverging ends of said main 115 arch, the top of said drop arch being of less curvature and lower than either of the other two arches, said by-pass arch being of a height substantially equal to the highest point of the main arch and of a width sub- 120 125 130

stantially equal to the widest part of said main arch, substantially as described and for the purposes stated.

10. A tunnel kiln comprising an elongated arch, means for supporting and moving ware through said kiln from its receiving end to its delivery end, the ware being stacked thereon in such a manner that a cooling or heating medium may be moved horizontally and transversely beneath the ware, thence vertically through said stack of ware upwardly or downwardly, the ware being
- so stacked that a passage will be provided longitudinally above the ware and a passage longitudinally on each side of the ware, 15 means for introducing and moving the cooling or heating medium longitudinally through one of said passages, and means for retarding the longitudinal movement of the cooling or heating medium to counteract the 20 momentum thereof and to deflect the medium transversely through the adjacent passages of said ware.

HALVER R. STRAIGHT.
